(57) **CLAIM**

(**) Term: **14 Years**

The ornamental design for a drill with unique shaped coolant holes, as shown and described.

(21) Appl. No.: **29/336,831**

DESCRIPTION

(22) Filed: **May 11, 2009**

FIG. 1 is a first perspective view of a drill with unique shaped coolant holes;

(30) **Foreign Application Priority Data**

FIG. 2 is a second perspective view thereof turned 90° from the first view of FIG. 1;

Nov. 28, 2008 (JP) 2008-030590

FIG. 3 is a front view thereof;

(51) **LOC (9) Cl.** **15-09**

FIG. 4 is a right side view thereof;

(52) **U.S. Cl.** **D15/139**

FIG. 5 is a top view thereof;

(58) **Field of Classification Search** D8/70;

FIG. 6 is a bottom view thereof;

D15/138, 139, 140; 83/845; 403/331, 381;
407/9, 33, 34, 42, 54, 63, 110, 113, 114,
407/115; 408/224, 226–230

FIG. 7 is a detail of the claimed design of the first perspective view thereof;

See application file for complete search history.

FIG. 8 is a detail of the claimed design of the second perspective view thereof;

(56) **References Cited**

FIG. 9 is a detail of the claimed design of a front view thereof;
FIG. 10 is a detail of the claimed design of a right side view thereof; and,

U.S. PATENT DOCUMENTS

FIG. 11 is an enlarged top view thereof.
